ELECTRIC DRIVE FOR DOMESTIC UTILITY
DEVICES

Wilhelm Weimers, Berlin, Germany, assignor to
Siemens - Schuckertwerke Aktiengesellschaft,
Berlin-Siemensstadt, Germany, a corporation
of Germany

Application December 22, 1932, Serial No.
648,359½. In Germany December 22, 1931

1 Claim. (Cl. 259—135)

My invention relates to a device provided with an electric drive adapted to operate domestic utility devices such as cleaning brushes, agitators for mixing drinks and the like.

The devices hitherto employed, deprived of a motor drive had to be operated manually. Recently, devices have been developed which are operated by motive power, but such apparatus are either driven by a flexible shaft by means of a stationary electric motor or they are secured to a pivotally mounted bracket which is fastened to the wall or the like. The devices heretofore employed have, on the one hand, the drawback that they are relatively unhandy and do not possess a sufficient flexibility and, on the other hand, are very expensive and require a particular care and maintenance.

The object of my invention is to provide a mixer whereby the foregoing drawbacks are overcome. To this end, the attachment, for instance, an agitator is secured to the armature shaft of an electric motor mounted in a casing serving as handle. A particularly advantageous construction consists in not securing the agitating attachment directly to the armature shaft but to a shaft extension which is associated with the armature shaft by means of a clutch which slips as a result of too great a torque. Such a device has the advantage in that it is easily flexible and may be easily manipulated without causing any fatigue as long as it is in operation. Moreover, the cost of manufacture of such a device is also reduced to a minimum. The device is fool-proof, since the entire casing of the device is made of insulating material. The slipping member provided for the drive prevents the motor from being exposed to too great a torque.

In the accompanying drawing an embodiment of my invention is illustrated partly in longitudinal section.

40

Referring to the drawing, 1 denotes a casing consisting of insulating material which serves at the same time as handle.

An electric motor 2 which may be connected to any suitable electric light socket by means of the cord 3 is securely mounted in the casing 1. Within the housing 1, a shaft member 5 is supported in axial alignment with the armature shaft of the motor 2 and connected to the shaft by means of a sliding clutch 6 which begins to slip as soon as the torque of the shaft 5 exceeds a predetermined value. At the lower end of the shaft member 5 an agitator 7 is wound in a manner as disclosed in the drawing.

Such an agitator has the advantage that it may be readily used by the housewife for whisking eggs, mayonnaise etc. As compared to the appliances hitherto employed and operated by hand the electric agitator according to the invention enables to do the work in a rapid manner and, if desired, the operation may be carried out for a long time without causing any fatigue.

Instead of an agitator other domestic attachments may be mounted on the shaft member 5.

I claim as my invention:—

A device for electrically driving domestic utility devices, comprising a handle, an electric motor securely supported in said handle, a removable tip on said handle and an operating shaft adapted to carry a utility device at its outer end and being journaled within said tip, and a slip clutch between said operating shaft and the motor shaft, said clutch consisting of the motor shaft end, split for a suitable length, and a coupling sleeve fixed on the operating shaft and frictionally engaging the split motor shaft end, said sleeve being located within said handle tip and held thereby in engagement with the motor shaft end.

WILHELM WEIMERS.
